LUGGAGE CARRIER OR THE LIKE

Frank G. Stone, North Long Beach, Calif., assignor to American Sports Co., Inc., Gardena, Calif., a corporation of California

Filed Aug. 20, 1964, Ser. No. 81,377

Term of patent 14 years

(Cl. D90—3)

FIG. 1.

FIG. 2.

FIG. 3.

FIG. 5.

FIG. 4.

FIG. 1 is a side elevational view of a luggage carrier or the like, showing my new design, the motorcycle shown in broken lines being included for illustrative purposes only;

FIG. 2 is an enlarged top plan view thereof;

FIG. 3 is an enlarged side elevation view thereof;

FIG. 4 is an enlarged rear end elevation view thereof;

FIG. 5 is a front end elevation view thereof.

I claim:

The ornamental design for a luggage carrier or the like, as shown and described.
